UNITED STATES PATENT OFFICE.

ROLAND SCARLET HOMAN, OF CHINO, CALIFORNIA.

MAIL-BOX.

1,245,719.

Specification of Letters Patent.

Patented Nov. 6, 1917.

Application filed July 11, 1917. Serial No. 179,935.

To all whom it may concern:

Be it known that I, ROLAND SCARLET HOMAN, a citizen of the United States, residing at Chino, in the county of San Bernardino, State of California, have invented a new and useful Mail-Box; and I do hereby declare the following to be a full, clear, and exact description of the invention, such as will enable others skilled in the art to 10 which it appertains to make and use the same.

The invention relates to improvements in rural mail boxes.

One of its objects is the provision of a 15 mail box which rural mail carriers will be enabled to open and close without having to leave their mail wagons.

Another object of the invention is the provision of a mail box having compartments for stamps and letters and a relatively large compartment for papers and magazines.

Still another object is to provide a mail box having a top capable of being raised 25 and means connected with the top whereby the latter is retained in a raised position while letters and papers are being transferred to the box, the means retaining the top in a raised position being capable of 30 tripping to effect the lowering of the top.

Other objects will appear in the detailed description which follows.

It is to be understood that the invention is not to be confined to the exact construction 35 herein disclosed, the right being reserved to make any changes or alterations falling within the scope of what is claimed.

In the drawings:

Figure 1 is a perspective view of the invention and the style of post on which it is 40 designed to be supported.

Fig. 2 is a section on the line 2—2 of Fig. 1.

Fig. 3 is a section on the line 3—3 of 45 Fig. 1.

Fig. 4 is a section on the line 4—4 of Fig. 1.

Fig. 5 is a section similar to Fig. 4 but shows the top of the box raised.

50 Referring to the drawings, the box is shown supported on the post 1 having an extending arm 2 at its top, the latter being braced by a diagonal member 3 fixed between it and the post 1. The box is supported on a bracket 4 to which it may be secured in any suitable manner and the bracket is

in turn attached to the post 1 but on such a side of the post that the box will project therefrom at right angles to the plane of the projecting arm 2. 60

The box comprises the bottom section 5 and the top section 6 which is hingedly connected to the bottom section by hinge members 7. The top section 6 being of substantially the same depth as the bottom section, 65 it is necessary that the box be positioned away from the post 1 to permit the raising of the top, and the box, therefore, is attached to the bracket 4 in such a manner as to permit a space to intervene between itself 70 and the post 1, as shown in Fig. 1. At the front of the box a hinge hasp 8 is provided and secured to the front of the movable top section 6. This hasp co-operates with the staple 9 fixed on the bottom section 5 and provides the means for locking the box when it is so desired. At the top of the hasp 8, there is formed an eye 10 to which a rope or cable 11 is attached, this cable passing over pulleys 12 secured at 75 either end of the projecting arm 2 and terminating in a knob 13 by which the top or cover section 6 may be raised. A spring 14 may be interposed in the cable 11 between the eye 10 and the first pulley on the arm 2, 80 this spring giving resiliency to the cable, if it is desired to add such a quality to the cable. It is to be observed that the slot 15 of the hasp 8 is designed to be made long enough, so as to become easily detached 85 from the staple after the padlock (not shown) has been disconnected.

At the forward end and to one side of the bottom section 5 two small compartments 16 and 17 are provided, the former for letters and the latter for change, stamps and the like. The compartment 16 is of the same depth as the bottom section 5, but the compartment 17 is made comparatively shallow with its upper edges flush with the upper edges of the lower section 5, as shown in the section in Fig. 2. 90

On the front and two sides of the box, beading 18 is attached to the lower edge of the cover section 6 and this beading overlaps the bottom section when the two sections are together and serves to keep the top section in alignment with the bottom section. 105

A compound lever is provided for keeping the top section in an elevated position after it has been raised by pulling on the 110

cable 11. This compound lever comprises a bell-crank lever 19 pivotally mounted on a screw 20 attached to one side of the cover section near the back end thereof. At the 5 end of the long arm 21 of this bell-crank lever a second lever 23 is pivotally mounted on the stud 22. The shorter arm 24 of the lever 23 overlaps the arm 21 of the bell-crank lever 19 and has secured to its end a 10 plate 25 disposed at right angles to both. The plate 25 is attached on the under edge of the lever 23, extending across the lower section 5 of the box on the interior but having a projecting end 26 which extends 15 across the arm 21 on the lower edge. A flat bowed spring 27 is suitably attached to the under edge of the arm 21 and presses upon the projecting end 26 of the plate 25 and thus operates to keep the lever 23 normally 20 in alinement with the arm 21 of the bell-crank lever 19. A pin 29 fixed in one side of the cover section 6 and to one side of the pivotal connection 20 is adapted to contact with the short arm 28 of the bell- 25 crank lever 19 to limit the movement of the latter on one side of its pivotal connection. A depression 30 is formed in the bottom of the lower section 5 and the free end of the lever 23 is adapted to engage this depression 30 when the cover section 6 is raised and when the short arm 28 of the bell-crank lever is in contact with the pin 29.

The box may be easily opened by a rural carrier while remaining in his carriage, the 35 operation of pulling on the cable 11 serving to raise the cover section 6. The upward movement of the latter allows the compound lever (composed of levers 19 and 23) to turn on its pivotal connection 20, the end of the 40 lever 23 dragging along the bottom of the lower section 5 until it falls in the depression 30 formed therein. The cover section 6 is then retained in an elevated position, since the arm 21 and lever 23 are held in 45 alinement with the spring 27. The carrier may then place his mail in the box, placing

letters in the compartment 16 and packages in the large compartment. The last package or paper to be placed in the box may be thrown upon the plate 25, thus tripping the 50 lever 23 from the depression 30 and permitting the cover section 6 to drop. The tripping operation is accomplished as a result of the manner in which the levers are assembled and mounted. The long arm 21 55 of the bell-crank lever is precluded from downward movement because of the short arm 28 being in contact with the pin 29 but the lever 23 is permitted movement on its pivotal connection 22 against the pressure 60 of the spring 27, the latter yielding from the weight imposed upon it by throwing the package upon the plate 25 which, moving downward, moves the short arm 24 downward and releases the end of the lever 23 65 from the depression 30, when the top section 6 drops restoring the levers to the position shown in Fig. 4.

What is claimed is:

A box adapted to receive packages and 70 the like comprising a bottom section and a top section hingedly connected together, a bell-crank lever pivoted on the top section, a straight lever pivoted to one arm of a bell-crank lever, a plate attached to the 75 straight lever and disposed at right angles to the length thereof, the bottom section having means to be engaged by the straight lever, the top section having means limiting the movement of the bell-crank lever, 80 and a resilient device holding the straight lever and bell-crank lever normally in alinement, whereby the top section may be held elevated when raised or lowered by tripping said straight lever.

In testimony whereof I have signed my name to this specification in the presence of two subscribing witnesses.

ROLAND SCARLET HOMAN.
